[57] CLAIM

The ornamental design for a combined brush and sponge, substantially as shown and described.

DESCRIPTION

FIG. 1 is a perspective view of a combined brush and sponge shown with the sponge portion, partly broken away, to complete the disclosure;

FIG. 2 is a side elevational view thereof;

FIG. 3 is an end elevational view thereof;

FIG. 4 is a bottom plan view thereof, shown in fragmentary form for convenience of illustration; and

FIG. 5 is a sectional view taken along the line 5—5 of FIG. 3;

The rows of bristles are continuous along the line indicated in FIG. 2 and are shown fragmentarily for convenience of illustration.

FIG.1

FIG.4

FIG.2

FIG.3

FIG.5
